UNITED STATES PATENT OFFICE.

MATTHEW G. COLLINS, OF YORK, PENNSYLVANIA, ASSIGNOR TO YORK SILK MANUFACTURING COMPANY, OF YORK, PENNSYLVANIA, A CORPORATION OF PENNSYLVANIA.

WOVEN FABRIC.

SPECIFICATION forming part of Letters Patent No. 746,465, dated December 8, 1903.

Application filed August 6, 1903. Serial No. 168,314. (No specimens.)

To all whom it may concern:

Be it known that I, MATTHEW G. COLLINS, a citizen of the United States, residing at York, in the county of York, State of Pennsylvania, have invented certain new and useful Improvements in the Manufacture of Woven Fabrics, of which the following is a description, reference being had to the accompanying drawing and to the letters of reference marked thereon.

My invention relates to improvements in the manufacture of fabrics, and particularly to the manufacture of woven silk fabrics.

It has been heretofore proposed in the manufacture of goods to weave into the body thereof letters, characters, or other designations of quality or ownership. In connection with the weaving of silk fabrics it happens that a greater or less proportion of the pieces woven have some defect or other and do not stand the tests of first-quality silks, which it is the practice of manufacturers now to guarantee. It is sometimes the practice to paste a slip containing a guarantee or evidence of quality or ownership upon the edges of pieces of silk; but this requires more or less labor, the strips are liable to be separated from the fabric, and there is nothing to prevent a dishonest retailer from utilizing strips which have been removed from guaranteed goods upon goods of inferior quality by pasting them upon such.

The present invention is designed to provide a simple and effective way of indicating the nature or quality or ownership of the goods, which shall protect in a most complete way the manufacturer as well as the purchaser, and which shall lessen the labor and cost to the manufacturer by leaving those pieces which can be guaranteed exactly as they come from the looms, while with those that cannot be guaranteed it is only necessary to sever the portion upon which the guarantee is placed.

The invention, therefore, may be said to consist, primarily, in an improvement in the manufacture of silk or other fabrics, comprising a woven body portion having simultaneously formed with it a narrow selvage edge strip upon which is placed the trade-mark,

guarantee, or other evidence of quality or ownership, certain of the threads adjacent the selvage edge strip and parallel therewith and between it and the finished edge of the body portion being omitted, so that the piece of goods comes from the loom finished complete with guarantee-strip and all; but if a piece is not of proper quality the strip containing the guarantee may be severed along the line where the threads were omitted.

Secondly, the invention comprises a silk fabric having a woven body portion provided with a selvage edge strip simultaneously woven with the body portion and having formed therein during the process of weaving letters or other characters indicating quality or ownership and having the edge of the body portion adjacent the selvage edge strip furnished and connected with the selvage edge strip by a woven portion from which a number of threads parallel with the edge strip have been omitted, whereby if the body portion of the goods is not up to standard the selvage edge strip containing the indications of quality or ownership may be severed from said body portion.

Thirdly, the invention comprises a silk fabric having a woven body portion provided with a selvage edge strip simultaneously woven with the body portion and having formed thereon during the process of weaving letters or other characters indicating quality or ownership and having the edge of the body portion adjacent the selvage edge strip finished and connected with the selvage edge strip by a woven portion from which a number of warp-threads have been omitted, whereby if the body portion of the goods is not up to standard the selvage edge strip containing the indications of quality or ownership may be severed from said body portion.

The invention is illustrated in the accompanying drawing, in which the figure represents a plan view of a fabric embodying my invention, the edge strip being shown as partially severed.

In the drawing the body portion A of the silk is woven upon a loom of usual construction, and at the same time the selvage edge strip B is woven letters, characters, or other

designations of quality or ownership, as at *b*, being interwoven with the edge strip. The body portion *A* of the fabric adjacent the edge strip is finished, as at *a*, so as not to unravel, certain of the warp-threads between the finished edge and the selvage edge strip being removed, so as to form a line upon which the severing of the edge strip and body fabric may be performed.

10 It will be seen by this construction that the guarantee edge strip, the letters or characters thereon, and the body portion are all woven simultaneously, and if the manufacturer cannot guarantee a piece which has been woven 15 all that it is necessary for him to do is to sever the guarantee-strip from the body portion.

Having thus described my invention, what I claim as new, and desire to secure by Letters 20 Patent, is—

1. As an article of manufacture, silk or other fabric, comprising a woven body portion having simultaneously formed with it a narrow selvage edge strip upon which are placed 25 letters or characters indicating quality or ownership, certain of the threads adjacent the selvage edge strip and parallel thereto, and between it and the finished edge of the body portion, being omitted; substantially as 30 described.

2. As an article of manufacture, silk fabric having a woven body portion provided with a selvage edge strip simultaneously woven with the body portion, and having formed therein

35 characters indicating quality or ownership, and having the edge of the body portion adjacent the selvage edge strip finished and connected with the selvage edge strip by a woven portion, from which a number of threads 40 parallel with the edge strip have been omitted, whereby if the body portion of the goods is not of proper quality the selvage edge strip containing the characters indicating quality or ownership may be severed from said body 45 portion; substantially as described.

3. As an article of manufacture, a silk fabric having a woven body portion provided with a selvage edge strip simultaneously woven with the body portion, and having formed thereon, 50 during the process of weaving letters or other characters indicating quality or ownership, and having the edge of the body portion adjacent the selvage edge strip finished and connected with the selvage edge strip, by a 55 woven portion from which a number of warp-threads have been omitted, whereby if the body portion of the goods is not up to standard, the selvage edge strip containing the indications of quality or ownership may be severed from said body portion; substantially as 60 described.

In testimony whereof I affix my signature in presence of two witnesses.

MATTHEW G. COLLINS.
